UNITED STATES PATENT OFFICE.

WARREN H. CRAIG, OF LAWRENCE, MASSACHUSETTS.

LUBRICATOR.

SPECIFICATION forming part of Letters Patent No. 281,241, dated July 17, 1883.

Application filed June 13, 1883. (No model.)

To all whom it may concern:

Be it known that I, WARREN HILLIARD CRAIG, of Lawrence, in the county of Essex, of the Commonwealth of Massachusetts, have 5 invented a new and useful Improvement in Steam-Engine Lubricators; and I do hereby declare the same to be described in the following specification, and represented in the accompanying drawings, of which—

10 Figure 1 is a vertical and transverse section of a lubricator provided with my invention, the nature of which is defined in the claims hereinafter presented. Fig. 2 is a similar section, but taken on a plane at right angles to 15 the plane of section of Fig. 1.

The lubricator hereinafter described is provided not only with means by or through which a person can see the drops of water as they pass from the condenser into the oil-reservoir, but with means by or through which he can also see the drops of oil as they may be discharged from the oil-reservoir and pass therefrom to the duct by which they are conveyed into the steam-engine cylinder or valve- 25 chamber thereof.

In the drawings, A denotes the condenser, having extending upward within it, nearly to its top, a pipe, B, which at its lower part is to communicate with the pipe for supplying 30 the engine with steam.

Below the condenser A is the oil-reservoir C, between which and the condenser is an oil-observation chamber, D, having a pane, a, of glass inserted in either or each of its opposite 35 sides. A tube, b, leads from the neck of the oil-reservoir into the observation-chamber D, in order to open communication between said neck and chamber.

In the upper part of the observation-chamber is an opening, e, by which communication 40 between the pipe B at its lower part or with the induct E, by which such pipe is to receive its steam, is secured:

From the foot of the condenser a passage, d, 45 leads down partly around the observation-chamber D into a valve-chamber, F, arranged horizontally within the neck of the oil-reservoir, such chamber being closed at its inner end, except in having an opening, e', at and 50 through the closure f. To this opening there

is a valve, g, whose stem h screws into a tubular projection, i, of the neck, a stuffing-box, k, being applied to the stem and projection.

Directly in front of the closure f there is an opening, l, in the neck of the oil-reservoir, 55 such opening having fitted into it a glass pane, m, which is arranged so close to the closure that a drop of water, after escaping from the valve-chamber F through the closure, shall touch both the pane and the closure in passing 60 down between them. This insures the drop being seen in case the pane may be clouded with steam or vapor or oil. The glass pane is also arranged so that each drop of water may freely escape from it into the reservoir. 65

At its lower end the oil-reservoir is furnished with a waste-cock, G, while at the upper part of its neck the oil-reservoir has an induct, H, for supplying it with oil, such induct not only having a lateral mouth, n, leading down into 70 it, but being provided with a screw, o, arranged, as shown, to effect the closing of such mouth at its lower part, as occasion may require.

The pipe B may be dispensed with and a 75 pipe may lead from the upper part of the condenser A directly into the steam-pipe; but in this case the observation-chamber must have communication with the said steam-pipe. From this it will be seen that with the pipe B 80 opening at its foot into the steam-induct but one such induct becomes necessary.

In the operation of this lubricator the steam flows from the steam-pipe into the pipe B, thence upward through and out of such pipe 85 into the condenser, where it becomes condensed, and in the form of water passes down into the valve-chamber and from thence into the oil-reservoir, and, descending through the oil therein, by its specific gravity, it will elevate the oil and cause it to flow into and through the observation-chamber, which will be filled with water by condensation of the steam. Owing to the water in the condenser standing 90 higher than the water in the observation-chamber, the water of the latter cannot pass down therefrom into the oil-reservoir. As each drop of oil may pass upward through the observation-chamber, such drop may be seen through its pane or panes of glass. 95 100

I am aware that a "displacement" lubricator, having an "observation-port" in front of the discharging-educt of the water-trap below the condenser, is not new; and therefore 5 I do not claim, broadly, a lubricator of such class provided with an opening port arranged to enable a person to see the water in its discharge from the water-trap. My lubricator, besides such a port, has an observation-chamber 10 arranged as described, whereby a person through a different port may see the oil in its discharge into the duct by which it is led to the steam-pipe.

I would further remark that I do not herein 15 claim a steam-engine lubricator consisting of a condenser and an oil-reservoir communicating with each other and having an oil-observation chamber arranged between them and means of communicating with the oil-reservoir 20 and the induct of the condenser, substantially as set forth, assuch forms the subject of another application for a patent filed by me February 21, 1883, and having the serial number 85,774.

I therefore claim—

25 1. A steam-engine lubricator provided not only with a condenser and an oil-reservoir having a communicating passage and a valve-chamber and valve thereto, as described, but with a glass port or pane in front of the valve-seat opening, and also having between such condenser and oil-reservoir an observation-chamber provided with one or more panes of 30 glass, and with passages or means of communication with the oil-reservoir and the steam-induct of the condenser, all being substantially 35 and for the purpose as set forth.

2. A steam-engine lubricator provided not only with a condenser and an oil-reservoir,

but having a valve-chamber and valve in the oil-reservoir, a passage leading from the condenser into the valve-chamber, and an observation-port or glass pane in front of the valve-seat opening, all being substantially as set forth, and the oil-reservoir having communication with the steam-induct, so as to enable 45 oil to pass from such reservoir into such induct.

3. A steam-engine lubricator provided not only with a condenser and an oil-reservoir, but having a valve-chamber and valve in the oil-reservoir, and also having an observation-port or glass pane in front of the valve-seat opening at a distance therefrom, such as will cause the drops of water discharged through the valve-seat opening to pass down in contact 55 both with the pane and the part containing such opening, all being essentially as shown and described.

4. The steam-engine lubricator consisting of the condenser, its induct and internal tube, 60 and eduction-passage, valve and valve-chamber, and oil-reservoir, provided with an observation-pane, arranged with the valve-seat, as set forth.

5. The steam-engine lubricator consisting 65 of the condenser, its induct and internal tube, eduction-passage, valve and valve-chamber, oil-reservoir, and observation-chamber, arranged and adapted substantially as set forth, such chamber being provided with one or more 70 glass panes, arranged in it as and for the purpose specified.

WARREN HILLIARD CRAIG.
